UNITED STATES PATENT OFFICE.

WILLIAM J. KING, OF PORTLAND, MAINE, ASSIGNOR TO THE E. T. BURROWES COMPANY, OF PORTLAND, MAINE.

POOL TABLE.

Application filed April 9, 1921. Serial No. 459,873.

To all whom it may concern:

Be it known that I, WILLIAM J. KING, a citizen of the United States, residing at Portland, in the county of Cumberland and 5 State of Maine, have invented certain new and useful Improvements in Pool Tables, of which the following is a specification, reference being had therein to the accompanying drawing.

10. My invention relates to improvements in a pool table and more particularly to a toy pool table of such size that it may be easily carried from place to place and placed upon a suitable support when it is desired to play 15 a game.

The principal object of the invention is the construction of the board in such a manner, and of such material, that it may be cheaply made and in carrying out this object I provide the table with cushions which are formed of wood or similar material and they are so connected to the table, or formed 20 an integral part thereof, that they will yield sufficiently to act as a cushion for the 25 balls used in playing the game.

A further object resides in the provision of novel forms of supports for the table, said supports acting as pockets for the reception of the game pieces used in playing 30 the game, or as means for limiting the movement of the game pieces through the 35 openings formed in the board.

With the above and other objects in view, which will appear as the description proceeds, my invention consists of the novel details of construction and arrangement of parts described in the following specification and illustrated in the accompanying drawings and while I have illustrated and 40 described the preferred embodiments of the invention it will be understood that such changes may be made as will fall within the scope of the appended claims.

In the drawings:

45. Figure 1 is a top plan.

Fig. 2 is a fragmental vertical section on the line A—A of Fig. 1.

Fig. 3 is a fragmental vertical section on the line B—B of Fig. 1.

50. Fig. 4 is a fragmental vertical section on the line C—C of Fig. 1.

Fig. 5 is a top plan of a slightly modified form of the invention.

Fig. 6 is a top plan of my game board showing the use of a modified form of support and pocket for the game pieces.

Fig. 7 is a side elevation showing the use of the modified form of support.

Fig. 8 is a detail perspective of one of the modified forms of support, and 60

Fig. 9 is a detail perspective of one of the members adapted to extend beneath the side openings in the board to limit the movement of the game pieces therethrough.

In the drawings, 1 indicates the longitudinally extending side rails and 2 the end rails going forward to make up the table and both the side and end rails are cut away along their bottom edges as indicated at 3 for forming a seat for the bottom 4, which I preferably make of a strip of paste board, or similar material, for the sake of cheapness.

Adjacent each corner the bottom 4 is formed with a circular opening 5 to receive 75 the reduced portion 6 of a combined support and pocket 7. As shown more particularly in Fig. 4 this combined support and pocket 7 is preferably in the form of a circular wooden block the upper surface of 80 which is concaved or cup shaped as indicated at 8. The concaved or cup shaped portion 8 will form a pocket for the reception of the balls used in playing the game. Openings 9 are also formed in the bottom 4, 85 adjacent the side edges, and midway of the ends, and these openings receive the combined supports and pocket 7 similar to those received in the corner openings. The pockets received in the openings 9 form the 90 usual side pockets of the pool table.

In Figs. 1, 2, 3 and 4, I have illustrated the cushions 10 as formed integral with the side and end rails 1 and 2, these cushions being formed by the longitudinally extending vertical openings 11 made in the side and end rails by a thin saw or similar tool. The side and end rails are left uncut at the corners 12 and at the points 13 so that they will be unyielding adjacent 100 the pockets. It will thus be seen that the cushions 10 are formed integral with, and

of the same material, as the side and end rails and will readily yield between the uncut portions.

In Fig. 5 I have illustrated a slightly modified form of the invention wherein the cushions are formed of flexible wooden strips 14 which are secured to the side and end rails 1 and 2 by means of nails 15 or similar fastening means. The strip 14 are spaced from the rails by the washers 16, through which the nails 15 extend, and as the strips 14 are of substantially thin material they will readily yield when struck by the balls used in playing the game. In all other respects the table will be constructed and supported, in the same manner as described for the preferred form. It will be understood that in each form of the invention the cushions will have their upper surfaces inclined downwardly and their under surfaces inclined upwardly forming the longitudinally extending nose or ridge 17.

In Figs. 6, 7, 8 and 9 I have illustrated a slightly modified form of support for the table and means for limiting the movement of the game pieces through the openings formed in the board. In the form of the invention illustrated in these figures, 17 represents the bottom having the openings 18 adjacent each corner and similar side openings 19 intermediate the corner openings. These openings 18 and 19 are adapted for the reception of the game pieces 20 which are preferably in the form of balls adapted for movement over the board by cues. Recesses 21 are formed in the under surface of the side and end rails 1 and 2 for receiving and connecting the supports 22 to the board. These supports 22 are preferably formed of small diameter wire bent to form the legs 23, the horizontally extending arms 24, and the vertically extending arms 25. When positioning the supports they will be arranged diagonally across the corners of the board, as more clearly indicated in Fig. 6 of the drawings, and the ends of the vertically extending arms 25 will be received in the recesses 21. As clearly seen the bending of the wire allows the arms 25 to be sprung for reception in the recesses and preferably the arms will tend to separate on reception in the recesses so as to securely connect the supports to the board and secure them in position by frictional engagement in the recesses. The horizontal arms 24 will extend under the openings 18 so as to limit the movement of the game pieces 20 through the openings. When the game pieces 20 are received in the openings they will rest upon the horizontally extending arms 24 and it will thus be seen that the supports not only support the board but at the same time, in reality cooperate with the openings 18 to form pockets for the reception of the balls. In Fig. 9 I have illustrated a member adapted for con-

nection to the side rails 1 in such a manner as to extend beneath the side openings 19 and to limit the movement of the game pieces therethrough. These members are formed of wire bent to form the vertically extending arms 26 and the horizontally extending portions 27. The ends of the vertically extending arms 26 are adapted for reception in recesses 28 formed in the under surface of the side rails. When the vertical arms are in position the horizontal portions 27 will extend beneath the openings 19 and thereby form a seat for the game pieces 20 which may be received in the said openings 19. When inserting, the arms 26 are preferably pressed towards one another so that when received in the recesses 28, they will spring outwardly thereby holding the member securely in position.

From the above detailed description it is thought that the construction and advantages of my table will be clearly understood and particularly the cheapness in manufacture. The cushions being formed of substantially thin strips of wood will readily yield and cushion the balls used in playing the game. At the same time the bottom is connected to the side and end rails in a novel manner and is of cheap material allowing the entire table to be constructed, at a cost within the reach of those in moderate circumstances and particularly adapting the table for use as a toy. The game pieces will be propelled by a cue such as is used in playing the game of pool and the number of the game pieces used will depend upon the particular game being played.

Having fully described my invention what I claim as new and desire to secure by Letters Patent is:

105

1. A game board comprising a bottom, sides, and ends, pockets carried by the bottom, and cushions carried by the sides and ends, said cushions being rigid adjacent the pockets but bodily flexible therebetween.

110

2. A game board comprising a bottom, sides and ends, and a cushion carried by the sides and ends, said cushion being spaced from the sides and ends and bodily flexible.

115

3. A game board comprising a bottom, sides and ends, and a cushion carried by the sides and ends, said cushion being formed of incompressible inelastic strips spaced from the sides and ends to allow them to be bodily flexed thereof.

120

4. A game board comprising bottom, sides and ends, and a yieldable cushion formed integral with the said sides and ends.

5. A game board comprising a bottom, sides and ends, and a yieldable cushion formed integral with the said sides and ends by forming longitudinally extending vertical openings through said sides and ends.

125

6. A game board comprising a bottom, sides and ends, the bottom having pocket

130

openings therein, and a yieldable cushion formed integral with the sides and ends by forming longitudinally extending vertical openings therethrough, said openings terminating adjacent the pocket openings whereby the cushion will be unyielding adjacent the said pocket openings.

In testimony whereof I hereunto affix my signature in the presence of two witnesses.

WILLIAM J. KING.
